[57] CLAIM

The ornamental design for a cutlery block, as shown and described.

DESCRIPTION

FIG. 1 is a side, top perspective view of a cutlery block showing our new design, the knife blade receiving slots shown in broken lines for illustrative purposes only and forming no part of the claimed design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof;

FIG. 7 is a right side elevation view thereof;

FIG. 8 is a side, top perspective view of an alternate embodiment of FIG. 1, the difference being in the differently sized openings of the knife slots;

FIG. 9 is a top plan view of FIG. 8; and,

FIG. 10 is a left side elevation view of FIG. 8.
